[57] CLAIM

The ornamental design for an illuminated key ring, as shown and described.

DESCRIPTION

FIG. 1 is a top, front and side, perspective view of an illuminated key ring showing my new design;
FIG. 2 is a front perspective view thereof;
FIG. 3 is a side perspective view thereof, the elevational view thereof opposite that shown in FIG. 3 being the mirror image thereof;
FIG. 4 is a rear perspective view thereof;
FIG. 5 is a top plan view thereof; and,
FIG. 6 is a bottom plan view thereof.
